(57) **CLAIM**

The ornamental design for a base plate with brick, as shown and described.

DESCRIPTION

FIG. 1 is a top, left, front perspective view of a base plate with brick showing my new design;

FIG. 2 bottom, right, rear perspective view of a base plate with brick showing my new design;

FIG. 3 is a front elevational view of the base plate with brick shown in FIG. 1;

FIG. 4 is a rear elevational view of the base plate with brick shown in FIG. 1;

FIG. 5 is a left side elevational view of the base plate with brick shown in FIG. 1;

FIG. 6 is a right side elevational view of the base plate with brick shown in FIG. 1;

FIG. 7 is a top plan view of the base plate with brick shown in FIG. 1;

FIG. 8 is a bottom plan view of the base plate with brick shown in FIG. 1; and,

FIG. 9 is a top, left, front perspective view of a base plate with brick, with the brick positioned on the base plate. The broken lines in FIG. 9 represent an example of additional block placement and forms no part of the claimed design.

1 Claim, 9 Drawing Sheets(56)
